UNITED STATES PATENT OFFICE.

GEORGE P. KINGSBURY, OF BROOKLYN, NEW YORK, ASSIGNOR TO MERGENTHALER LINOTYPE COMPANY, A CORPORATION OF NEW YORK.

TYPOGRAPHICAL MACHINE.

1,103,363.

Specification of Letters Patent. Patented July 14, 1914.

Application filed October 31, 1913. Serial No. 798,419.

To all whom it may concern:

Be it known that I, GEORGE P. KINGSBURY, a citizen of the United States, residing at Brooklyn, in the county of Kings and State 5 of New York, have invented certain new and useful Improvements in Typographical Machines, of which the following is a specification, reference being had therein to the accompanying drawing.

10 My invention relates to typographical machines, such as linotype machines of the general organization represented in Letters Patent of the United States, No. 436,532, to O. Mergenthaler, wherein circulating matrices 15 are released from a magazine or magazines in the order in which their characters are to appear in print and then assembled in line, the composed line transferred to the face of a mold, the mold filled with molten metal to 20 form a slug or linotype against the matrices which produce the type characters thereon, and the matrices thereafter returned through distributing mechanism to the magazine or magazines from which they started. More 25 particularly, it relates to machines of this character adapted to carry a number of fonts or sets of matrices representing different sizes or styles of type, in such manner that any font may be brought into action at will. 30 I have illustrated my invention as applied to the style of machine presented in Letters Patent of the United States, No. 848,771, to John R. Rogers, wherein is employed a plurality of fixed magazines, in combination 35 with a movable bridge for directing the matrices from a selected one to a common assembling mechanism, and with shiftable actuating devices which are simultaneously brought into operative relation to the escapements thereof. The adjustment of the 40 last mentioned parts is effected by the operation of a handle and mechanism connected thereto. It is the purpose of my present invention to simplify the arrangement, and to 45 that end I preferably mount the bridge and escapement actuating connections upon a support which may be manually removed from one operative position and reinserted in another. The specific construction will be

described more at length in the following 50 specification, and the invention pointed out finally in the claims.

Referring to the drawings, I have shown my invention only in preferred form and by 55 way of example, and as applied to the specific style of machine indicated, but obviously many changes and variations may be made therein, and in its mode of application, which will still be comprised within its spirit; and it may be similarly adapted to other forms 60 of typographical machines, such as typesetters, typecasters and the like, which handle type or dies, instead of matrices.

Generally speaking, I desire it to be understood that I do not limit myself to any 65 specific form or embodiment, except in so far as such limitations are specified in the claims.

Referring to the drawings: Figure 1 is a front elevation, partly broken away, of a 70 linotype machine having my invention applied thereto; Fig. 2 is a section, on an enlarged scale, taken substantially on the line 2-2 of Fig. 1; and Fig. 3 is a detached perspective of the bridge, its supporting means, 75 etc.

As is usual in machines of this kind, such for instance as in the "Model 9" linotype or the said Rogers patent, a plurality of fixed superposed magazines A is employed, and 80 the matrices released from the one in action pass onto the belt B, and from it in turn to the assembler C. Between the magazine and the belt is interposed the front plate D provided with vertical partitions D¹, constituting 85 a raceway which insures the correct delivery of the matrices. The bridge E is located between the front plate and the magazine to guide and direct the matrices, and this bridge is vertically adjustable to different 90 operative positions, so that one or another of the magazines may be selected and called into action at will. The parts so far described are or may be of any suitable form, and their exact construction constitutes no 95 part of my present invention, except as hereinafter specified.

In order to simplify the existing construc-

tion, I preferably mount the bridge E upon the detachable frame F, formed at its bottom with projecting flanges F¹ designed to engage in one or another pair of the horizontal grooves G¹ formed in the support G, the grooves G¹ being so located and disposed as to maintain the bridge in operative relation to any selected magazine, in the manner understood by those skilled in the art.

10 The frame F carries vertical partitions E¹ corresponding to and registering with the partitions D¹ of the front plate, and also the vertical guide plate E² adapted to bear against the partitions D¹ of the front plate 15 and close its underlying channels at the rear.

The frame F is preferably provided with a handle F², whereby the frame may be conveniently withdrawn laterally from the machine, and reinserted. Fig. 1 shows the 20 frame partially withdrawn, and indicates in dotted lines its position prior to its replacement in another operative position.

25 The magazines A are each provided with a series of escapements H, those of the selected one being actuated by the vertically movable bars J, which are formed with a series of vertically-disposed notches J¹, adapted to engage according to their position with the levers K, which in turn are operated by the customary reeds K¹, substantially in the manner indicated in the said 30 Rogers patent. The actuating bars J are also mounted upon the frame F and are consequently adjusted therewith, so that when 35 the bridge E is shifted into registry with a chosen magazine, the bars J are similarly moved into operative relation to the escapements H thereof, and simultaneously the appropriate series of notches J¹ are brought 40 into engagement with the operating levers K.

45 As previously stated, I have shown my invention only in preferred form and by way of example, and as applied to a specific kind of machine, but obviously many modifications and alterations therein, and in its mode of adaptation, will suggest themselves to those skilled in the art, without departure from its scope.

50 Having thus described my invention, its construction and mode of operation, what I claim and desire to secure by Letters Patent of the United States, is as follows:

55 1. In a typographical machine, the combination of a plurality of magazines, a raceway common to all the magazines, an intermediate bridge, and a plurality of supports upon one or another of which said bridge may be mounted so as to be set in operative 60 relation to one or another of the magazines, said bridge being removable at will from said supports so as to be mounted upon any selected one thereof.

2. In a typographical machine, the com-

bination of a plurality of inclined magazines, 65 an upright raceway common to all of the magazines, and an intermediate bridge in operative relation to one of the magazines, said bridge being removable from the machine at will and replaceable 70 in operative relation to a different magazine.

3. In a typographical machine, the combination of a magazine, a raceway to receive the matrices therefrom, and an intermediate 75 bridge to carry the matrices from the magazine to the raceway, said bridge being detachably mounted in the machine in such manner as to be removed laterally therefrom freely and at will.

4. In a typographical machine, the combination of a magazine, a raceway to receive the matrices therefrom, an intermediate bridge to carry the matrices from the magazine to the raceway, and a fixed support for 85 the bridge, said bridge being detachably connected to the support so as to be removable therefrom independently of the other parts.

5. In a typographical machine, the combination of a plurality of stationary magazines, each provided with a series of escapements, a series of actuating devices, and a plurality of supports upon one or another of which the actuating devices may be 95 mounted so as to be set in operative relation to the escapements of one or another of the magazines, the said actuating devices being removable at will from the supports so as to be shifted from one to another thereof 100 when desired.

6. In a typographical machine, the combination of a plurality of magazines each provided with a series of escapements, a single series of actuating devices in operative relation to the escapements of one of the magazines, and a supporting frame for the actuating devices, said frame being removable from the machine at will and replaceable in a different position to locate the actuating devices in operative relation to the escapements of a different magazine.

7. In a typographical machine, the combination of a plurality of magazines each provided with a series of escapements, a 115 raceway common to all the magazines, a supporting frame provided with a bridge to carry the matrices from the magazines to the raceway and with a series of escapement actuating devices, the said frame being removable from the machine at will and replaceable in operative relation to one or another of the magazines.

8. In a typographical machine, the combination of a magazine provided with a series of escapements, a raceway to receive the matrices therefrom, an intermediate bridge to carry the matrices from the magazine to

the raceway, a series of actuating devices for the escapements, and a supporting frame for both the bridge and escapement actuating devices, the said frame being detachably mounted in the machine so as to be removable therefrom independently of the other parts.

In testimony whereof I have affixed my signature in presence of two witnesses.

GEORGE P. KINGSBURY.
